SPLINE LAPPING MACHINE

Michel P. Heldt, Detroit, Mich., assignor to Vinco Corporation, Detroit, Mich., a corporation of Michigan

Filed Oct. 26, 1967, Ser. No. 9,179

Term of patent 14 years

Int. Cl. D15—05

U.S. Cl. D55—1

FIG. 1

FIG. 2

FIG. 4FIG. 3FIG. 1 is a side elevational view of a spline lapping machine embodying my novel design.

FIG. 2 is a front elevational view of the same.

FIG. 3 is a rear elevational view of the same.

FIG. 4 is a plan view of the same.

The broken line representation of the handle elements disclosed in FIG. 4 have been partially omitted in FIGS. 1 and 2 for ease of illustration.

The dominant features of my design reside in the portions shown in full lines.

I claim:

The ornamental design for a spline lapping machine, as shown and described.
